UNITED STATES PATENT OFFICE

ALBERT HOLMQUIST, OF HOLMQUIST, SOUTH DAKOTA

MIXING MACHINE

Application filed July 6, 1932. Serial No. 621,098.

The present invention relates to a mixing machine which is intended particularly for use in treating and mixing grain and feed and has for its primary object to provide, in a manner as hereinafter set forth, a device of this character which is manually operable and which includes a novel construction, combination and arrangement of parts through the medium of which a conventional container, such as a milk can, may be removably mounted for rotation in a vertical plane.

Other objects of the invention are to provide a mixing machine of the aforementioned character which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in front elevation, showing a mixing machine constructed in accordance with the present invention.

Figure 2 is a view in side elevation thereof. Referring now to the drawings in detail, it will be seen that the embodiment of the invention which has been illustrated comprises a supporting structure which is designated generally by the reference numeral 1.

The supporting structure 1 includes spaced, parallel, vertical standards 2 which rise from the horizontal feet 3 to which said standards are fixed at their lower ends. The supporting structure 1 further includes braces 4 which extend between the standards 2 and the end portions of the feet 3 and crossed braces 5 extending between said standards.

Journalized in the upper end portions of the standards 2 of the supporting structure 1 are aligned shafts 6, one of which has fixed thereon an actuating crank 7. Fixed on the inner ends of the shafts 6 are elongated blocks or heads 8 of wood or metal tubing

which are engageable longitudinally with the sides of a container which may be in the form of a conventional milk can 9. The shaft 6 on which the crank 7 is mounted may be slidably adjustable in its respective supporting standard 2 to adapt the machine for containers of various sizes.

Upper and lower pairs of arcuate, metallic clamping straps 10 have threaded bolts 11 secured, as at 12, on their end portions, said bolts 11 extending angularly from the straps and being insertable through inclined openings provided therefor in the upper and lower portions of the blocks 8. Winged nuts 13 are threaded on the free end portions of the bolts 11 for drawing the straps 10 tightly around the container 9.

The reference numeral 14 designates a closure for the container 9, said closure being detachably secured in position through the medium of a bar 15 extending thereacross and projecting therebeyond and to the end portions of which are secured hooks 16 which are connected to handles 17 on the container 9. Nuts 18 are threaded on the upper end portions of the hooks 16 and bear on the bar 15 for clamping the cover 14 in position.

In use, the material to be mixed or otherwise treated is placed in the container 9, after which the closure 14 is secured in position. The container 9 is then rotated in a vertical plane through the medium of the hand crank 7, as will be apparent. If desired, the material to be mixed may be placed in the container 9 after which said container 9 may be mounted in position between the blocks 8.

It is believed that the many advantages of a mixing machine constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A mixing machine comprising a supporting structure, a pair of aligned, spaced

shafts journaled on the supporting structure, elongated members fixed on the inner end portions of the shafts for rotation therewith, said members having pairs of openings extending transversely through their end portions, upper and lower pairs of arcuate straps engageable with the container, bolts on the end portions of the straps insertable through the openings, and nuts threaded on the bolts and engageable with the members for clamping the straps around the container.

2. A mixing machine comprising a supporting structure including a pair of spaced, parallel standards, a shaft journaled in one of the standards, another shaft rotatably and slidably mounted in the other standard in spaced, aligned relation to the first named

shaft, an actuating crank fixed on the second named shaft, a pair of elongated members fixed on the inner end portions of the tabs at right angles thereto, each member having a pair of inclined openings extending transversely through each end portion, pairs of arcuate, metallic straps engageable with a container for removably mounting said container on the shafts, bolts fixed on the end portions of the straps and engageable in the openings of the members, and nuts threaded on the bolts and engageable with the members for clamping the straps against the container.

In testimony whereof I affix my signature.

ALBERT HOLMQUIST.
